UNITED STATES PATENT OFFICE.

EDGAR J. CARROLL, OF WORCESTER, ASSIGNOR TO GEORGE DRAPER & SONS, OF HOPE DALE, MASSACHUSETTS.

SPINDLE-SUPPORT.

SPECIFICATION forming part of Letters Patent No. 352,222, dated November 9, 1826.

Application filed June 22, 1826. Serial No. 205,884. (No model.)

To all whom it may concern:

Be it known that I, EDGAR J. CARROLL, of Worcester, county of Worcester, and State of Massachusetts, have invented an Improvement in Spindle-Supports, of which the following description, in connection with the accompanying drawings, is a specification, like letters on the drawings representing like parts.

This invention has for its object to improve the construction of that class of spindle-bearings in which the lateral bearing or the pintle of the spindle for holding the foot of the spindle is located above the base or top of the bolster or step-rail, the said bearing being supported in a yielding manner, whereby usual supporting-tubes containing independent loose bolsters surrounded by fibrous packings or oil are dispensed with.

In accordance with my invention, a rigid tube-like bearing to receive the pintle of the spindle and be surrounded by the sleeve-whirl has a foot, which is located above the surface of the usual bolster or step-rail, the said foot having at or near one extremity thereof a vertical flange or extension, which is attached loosely by a suitable screw or pivot to a rigid face formed upon a base; or it may be the bolster or step-rail, the base being, however, preferable because of cheapness of construction.

Figure 1, in vertical section, shows a spindle-bearing, base, rail, and sleeve-whirl embodying my invention, the spindle being in elevation. Fig. 2 is a top or plan view of the bearing and base alone. Fig. 3, in elevation, shows a modified form of bearing embodying my invention as attached to a rail, the latter being in section; and Fig. 4 is a top or plan view of the bearing shown in Fig. 3, its top foot being partially broken out to show the screw or bolt for attaching it to the base.

The bolster or step-rail A, the spindle B, having the sleeve-whirl B', and the pintle B'' are all as common. The rail A has secured to it by a nut, C, a base, D, which rests upon the surface of the rail, and is provided with a face, D', preferably made as an ear, located substantially at right angles to the level of the top of the rail A.

My improved bearing consists, essentially,

of a rigid stiff tube, E, having a foot, E', the said tube receiving in its bore the pintle B'' of the spindle, and being surrounded externally by the sleeve-whirl, the foot of the bearing in the present invention containing also the block 55 a, which constitutes the step for the pintle. This bearing E E' has at one end an ear, E'', which is joined loosely to the vertical face D' by a pin or bolt, D'', the said pin being extended loosely through one and screwed or 60 fixed to the other, as shown best in Fig. 1, a yielding packing, as at b, being preferably interposed between the said ears to constitute a cushion and afford the bearings E E' an opportunity to give or yield as the lower end or 65 foot of the spindle vibrates or shakes when the spindle is rotated rapidly or is unevenly loaded, the said packing allowing the bearing to yield more readily than were it omitted and the ear E'' were brought firmly in contact with 70 the face D', only the elasticity in the ear E'' being in such case available to permit a limited amount of vibration of the bearing with relation to the base or rail.

To prevent undue vibration of the bearing 75 E E' about the locking screw or stud as a center, I have provided the base with a pin or stud, d, which enters a hole or recess of larger diameter in the foot D of the bearing.

Referring to the drawings, Figs. 3 and 4 80 showing a modification of my invention, it will be noticed that the ear E'' is directed vertically downward from the foot of the bearing, instead of upward, as in Figs. 1 and 2, and that the face D' forms part of one side of the base 85 or rail A, the ear E'' being connected to the face D' by means of two locking bolts or screws, D'', which are passed through the ear E'' loosely, and into screw-threaded portions of the rail, a fibrous or elastic packing of textile or other 90 usual material being interposed between the face D' and the ear E'', the under side of the bearing being supported above the top of the rail A.

By employing the two screws D'', as in Figs. 95 3 and 4, instead of one, as in Fig. 1, the pin or projection d is rendered unnecessary.

I do not claim a bolster having at one side of it a socket, which is fitted over a pin and fastened to the same.

I claim—

1. A spindle-bearing composed, essentially, of a rigid tube, E, having a foot provided with an ear, E², extended therefrom parallel with the spindle, substantially as described, combined with a face or abutment, to one side of which the said ear is attached loosely, and means to attach the said ear to the said face loosely, substantially as set forth.
- 10 2. A spindle-bearing composed, essentially, of a rigid tube, E, having a foot provided with an ear extended therefrom, substantially as described, combined with a face or abutment

to which the said ear is secured, an interposed packing, and means to loosely connect the said ear with the said face, the foot of the bearing being supported above and externally with relation to the bolster or step-rail, substantially as described.

In testimony whereof I have signed my name 20 to this specification in the presence of two subscribing witnesses.

EDGAR J. CARROLL.
